METHOD OF LASTING OPEN-TOE SHOES

Jacob S. Kamborian, West Newton, Mass.

Application September 22, 1943, Serial No. 503,340

9 Claims. (Cl. 12—145)

1

This invention pertains to the manufacture of footwear and relates more particularly to a novel method of lasting open-toe shoes. It is very difficult to last the open-toe type of shoe by the usual lasting machine, since there is no material at the center of the toe end of the upper which may be seized by the center jaw of the pulling-over machine. Consequently hand lasting has been resorted to but even by hand lasting it is difficult to obtain satisfactory results, since the material at opposite sides of the toe notch must be stretched independently.

The principal object of the present invention is to provide a novel method of lasting open-toe shoes, particularly shoes which are also open at the heel, whereby in a simple and inexpensive manner to insure a satisfactory degree of stretch of the forepart material at the toe and concomitantly to assure a proper location of the toe opening. A further object is to provide a novel method of lasting open-toe shoes which can be performed without special skill and without the use of special or complicated machinery. Other and further objects and advantages of the invention will be pointed out in the following more detailed description and by reference to the accompanying drawing wherein

Fig. 1 is a plan view of the vamp of an open-toe, open-heel shoe;

Fig. 2 is a bottom view of the forward end of the vamp as it appears at the completion of the first step of the present novel method;

Fig. 3 is a front elevation of the vamp of Fig. 2;

Fig. 4 is a plan view of a shoe upper mounted on a last;

Fig. 5 is a side elevation of a lasted shoe; and

Fig. 6 is a bottom view of a last of special design useful in the performance of this novel method.

Referring to the drawing, the numeral 1 designates a shoe vamp appropriate for use in making a shoe of the open-toe, open-heel type. This vamp is cut away at the points 2 to provide the rearwardly extending portions 3 to which the strap members 4 (Fig. 5) are attached. At its forward end the vamp is provided with a notch 5 intervening between two forwardly directed tabs 6 and 7. After preparing this vamp (or the shoe upper embodying the vamp) the tabs 6 and 7 are brought together in overlapping relation as shown in Fig. 2, and are united by barring stitches 8 or one or more staples, or otherwise, thus defining an opening 9 at the toe end of the shoe.

Prior to assembling the upper with the last

2 a suitable insole will be tacked to the last bottom in accordance with usual procedures.

The upper is slipped over the last and drawn backwardly so that the tip 11 of the last projects through the opening 9 and distends the latter. 5 The operator twists the upper upon the last until the upper is properly aligned relatively to the last, thus performing the "spindling" operation, and then exerts rearward stress upon the vamp by drawing the strap member 4 about the rear end of the last and tightening the strap. If preferred the strap may be buckled before the upper is placed upon the last and then snapped over the last so as to obtain the desired tension. After 10 thus mounting the upper upon the last (an operation which takes the place of the usual pulling-over operation) the lasting may be completed in any desired manner as for example by the use of a lasting machine such as disclosed in the patent to Kamborian No. 2,251,284, dated August 5, 1941.

If the tabs are to be overlapped as above suggested they may be skived to reduce the thickness of the material where they overlap. Instead of 15 overlapping the tabs 6 and 7 they may be brought into edge-to-edge relation and united for example by barring stitches. In fact the tabs as such may be omitted, the forward end portions of the vamp proper at opposite sides of the toe 20 notch being placed edge-to-edge or otherwise suitably juxtaposed and united by barring stitches, staples or otherwise.

While an ordinary last may be employed, it 25 may be desirable if the tip of the last be too blunt to enter the opening 9, to provide the last with an auxiliary tip piece of tapering form as illustrated in Fig. 6. The more or less conical tip 11^a of the last 10^a is a separate piece secured in any appropriate way to the last proper. By the 30 employment of such a conical tip it is possible to adapt lasts of the more or less square toed type for use in the practice of this process.

While certain desirable arrangements and procedures have herein been described it is to be 35 understood that the invention is broadly inclusive of any and all equivalent arrangements and procedures falling within the scope of the appended claims.

I claim:

50 1. That method of lasting open-toe shoes which comprises as steps providing an upper and an insole, which upper includes a vamp having a notch at its forward end, bringing the forward end portions of the vamp material at opposite sides of the notch into juxtaposition, uniting said

portions to define an opening at the toe end of the upper, assembling the insole with a last, slipping the upper over the last and insole and drawing it backwardly so that the tip of the last registers with the opening at the toe end of the upper, spindling the upper and lasting the upper to the insole.

2. That method of lasting open-toe shoes which comprises as steps providing an upper and an insole, said upper including a vamp which terminates at its forward end in a pair of tabs separated by a notch, disposing said tabs in overlapping relation, uniting the tabs to define a toe opening, assembling the insole with a last, slipping the upper over the assembled insole and last so that the tip of the last registers with the toe opening in the upper, spindling the upper, and applying longitudinally exerted stress thereto, thereby conforming the vamp to the forepart of the last and lasting the upper to the insole.

3. That method of lasting open-toe shoes which comprises as steps providing an upper and an insole, said upper including a vamp which terminates at its forward end in a pair of forwardly directed spaced tabs and has an ankle strap at its rear end, disposing the tabs in overlapping relation and uniting them to define a toe opening, assembling the insole with a last, slipping the upper over the assembled insole and last so that the tip of the last registers with the toe opening in the upper, spindling the upper, tightening the strap about the rear end of the last thereby stressing the upper rearwardly, and drawing the vamp snugly about the forepart of the last and lasting the upper to the insole.

4. That method of lasting open-toe, open heel shoes which comprises as steps providing an upper and an insole, said upper including a vamp which terminates at its forward end in a pair of spaced tabs and has an ankle strap at its rear end, disposing the tabs in juxtaposition and uniting them to provide a toe opening, assembling the insole with a last, slipping the upper over the insole and last so that the tip of the last registers with the toe opening in the upper, spindling the upper, uniting the ends of the strap to form a loop; snapping the loop over the rear end of the last thereby stressing the upper rearwardly and drawing the vamp snugly about the forepart of the last and lasting the upper to the insole.

5. Method of lasting an open-toed shoe of the kind which, when completed, includes a bottom structure and an upper, the upper having an opening at its toe end located above the level of the foot-supporting surface of the bottom structure, said method comprising as steps providing an upper including a vamp having a substantially V-shaped notch at its forward end bringing the forward end portions only of the vamp material, at opposite sides of the notch, into juxtaposition and permanently uniting them, thereby to define an opening of substantially fixed peripheral extent in the toe end of the upper, introducing a last into the upper and forcing its toe end into said opening, and applying longitudinal stress to the upper thereby to draw its forepart snugly about the forepart of the last.

6. Method of lasting an open-toed shoe of the kind which, when completed, includes a bottom structure and an upper, the upper having an 70

opening at its toe end located above the level of the foot-supporting surface of the bottom structure, said method comprising as steps providing an upper whose vamp terminates at its forward end in a pair of tabs separated by a notch, disposing the tabs in overlapped relation and permanently uniting said tabs by a fastener element thereby to define a toe opening of substantially fixed peripheral extent while leaving the margins of the upper rearwardly of said tabs free from each other, introducing a last into the upper so that its tip protrudes into said opening, spindling the upper, and applying longitudinal stress to the upper thereby to conform the vamp to the forepart portions of the last.

7. Method of lasting an open-toed shoe of the kind which, when completed, includes a bottom structure and an upper, the upper being open at its heel end and having, at its toe end, an opening 10 located above the level of the foot-supporting surface of the bottom structure, said method comprising as steps providing an upper having a vamp which terminates at its forward end in a pair of forwardly directed tabs, the upper having an 20 ankle strap at its rear end, disposing the tabs in overlapped relation and permanently uniting them thereby to provide the upper, at its toe end, with an opening of substantially fixed peripheral extent, inserting a last into the upper and causing its tip to enter the opening at the toe end of the upper, and stressing the upper rearwardly by tightening the strap about the rear end of the last, thereby to draw the vamp snugly about the forepart of the last.

8. Method of lasting an open-toed shoe of the kind, which when completed, includes a bottom structure and an upper, the upper being open at its heel end and having, at its toe end, an opening 30 located above the level of the foot-supporting surface of the bottom structure, said method comprising as steps providing an upper having a vamp which terminates at its forward end in a pair of spaced tabs, the upper having an ankle strap at its rear end, disposing the tabs in overlapping relation and permanently uniting them, 40 thereby providing the upper, at its toe end, with an opening of substantially fixed peripheral extent, inserting a last into the upper and causing its tip to enter the opening at the toe of the upper, uniting the ends of the ankle strap to form a loop and snapping the loop over the rear end of the last thereby to stress the vamp about the forepart of the machine.

9. That method of lasting an open-toed shoe 50 of the kind, which when completed, includes a bottom structure and an upper, the upper having, at its toe end, an opening located above the level of the foot-supporting surface of the bottom structure, said method comprising as steps providing an upper including a vamp having a substantially V-shaped notch at its forward end, permanently uniting the forward end portions only of the vamp at opposite sides of the notch, thereby to provide the upper at its toe end with 60 an opening of substantially fixed peripheral extent while leaving the lower lateral margins of the upper, rearwardly of said opening, free from each other.

JACOB S. KAMBORIAN.
